UNITED STATES PATENT OFFICE.

RUDOLPH GIEBERMANN, OF CHICAGO, ILLINOIS, ASSIGNOR OF ONE-HALF TO
THE BOUTON FOUNDRY COMPANY, OF SAME PLACE.

FILTER-PRESS.

SPECIFICATION forming part of Letters Patent No. 445,053, dated January 20, 1891.

Application filed May 17, 1890. Serial No. 352,254. (No model.)

To all whom it may concern:

Be it known that I, RUDOLPH GIEBERMANN, a citizen of the United States, residing in the city of Chicago, in the county of Cook and State of Illinois, have invented certain new and useful Improvements in Filter-Presses, of which the following is a specification.

This invention relates to improvements in filter-presses for expressing and separating the liquid from the solid portion of the material being operated upon, but is more especially designed as an improvement upon the presses heretofore employed for expressing the liquid from the solid portion of distillery-swill for the purpose of converting the same into an article of commerce.

Prior to this invention a series of hollow thin filter-plates have been employed, into each of which the swill has been forced, and in which the cakes are formed of a necessarily-limited thickness, because of the compression required and the manner of feed of the swill thereto.

The prime object of this invention is to form cakes of any desirable size or thickness and in a more rapid and effective manner than heretofore.

Another object is to have the cakes formed in frames separate from the filter-plates, but interposed therebetween, whereby the cakes may be removed independent of the filter-plates and the latter immediately employed in the formation of new cakes.

A further object is to dispense with the employment of the filter-plates in which to form the cakes and to utilize the same solely as separators and filters for the frames in which the cakes are formed, whereby the expressing of the liquid from the cake is materially facilitated and the rapidity of the work correspondingly promoted. These objects are attained by the devices illustrated in the accompanying drawings, in which—

Figure 1 represents a perspective view of a filter-press embodying my invention, showing most of the frames and filter-plates removed; Fig. 2, a central longitudinal vertical section thereof; Fig. 3, a detail sectional elevation of one of the filter-plates with one of the perforated plates thereof removed to more clearly

disclose the internal construction thereof; Fig. 4, a transverse vertical section of the same; Fig. 5, a detail perspective view of a removable filling-sleeve, and Fig. 6 an enlarged detail section through the support of the distance-frame.

Similar letters of reference indicate the same parts in the several figures of the drawings.

Referring by letter to the accompanying drawings, A B indicate two vertical end frames or standards connected at the center near the bottom by a supporting-rod C and centrally upon each side by guide-rods D, which latter may in turn be strengthened about the center of length thereof by legs or braces E, the whole constituting the main or supporting frame of my machine, upon which all of the operating parts thereof work.

The end or standard A is solid and immovable, and constitutes the support against which the distance-frames and filter-plates are forced preparatory to filling and expelling the piston-head F, guided by eyes G thereon, sliding upon the rod D, and actuated by the piston-rod H of a hydraulic ram I, (not shown in detail,) guided and supported in a suitable boxing J, formed in the end frame B of the machine.

The construction and operation of the ram form no part of this invention, and I may here state that, if desirable, any other means of compression—such as the common and well-known screw—may be substituted therefor without departing from the spirit of my invention, the ram being preferred, however, on account of the rapidity and effectiveness of its operation.

Between the end frame A and the piston-head is arranged a series of distance-frames K and filter-plates L, alternating with each other, and of such dimensions as to fit between the guide-bars D, the filter-plates being directly supported upon the bar C, while the distance-frames are supported upon the guide-bars by means of rollers M, mounted upon shortshafts N, journaled in suitable brackets O, projecting from the sides of and cast with or otherwise rigidly secured to said frames, these rollers preferably running upon suit-

able depressions formed in the upper surface of the guide-bars D, although they may be concaved to fit the bars and accomplish the same end. By this arrangement the weight 5 of the distance-frames is directly supported upon these guide-bars, and they are readily movable theron, the outer ends of the shafts N being squared for reception of a crank-handle, by means of which the frames may 10 be easily moved back and forth. These distance-frames consist of an open rectangular frame, the upper bar of which is provided at its center of length on each side with depending perforated lugs P and on top thereof 15 with a boss Q, to which is attached one end of a feed-pipe R, leading down from the main feeder S, through which the swill in its semi-liquid state is forced into the frame. The filter-plates are also open rectangular frames 20 of substantially the same contour and dimensions as the distance-frames, and their upper bar is likewise provided at its center of length with a depending perforated lug T, adapted and arranged to register with the lugs P of the 25 distance-frames, so that when the frames and plates are set side by side, as illustrated in the drawings, alternating with each other, all of the perforations in the lugs of both frames will register with each other, but not form a 30 continuous passage, as the continuity thereof is interrupted at each distance-frame, which, as shown, is provided at the side edges thereof only with the depending lugs. The perforation in the end filter-plate, however, registers 35 with the end of a supplemental feed-pipe U, passing through the end frame A, so that as the swill is forced therein it will pass entirely through the filter-plate, but fall into the distance-frame which is being simultaneously 40 fed through the overhead pipe R until the frame becomes filled, when it will pass on through the perforation in the next filter-plate and into the next distance-frame, and so on until all of the frames are filled.

45 Each of the filter-plate frames, as will be more clearly seen by an inspection of Fig. 3, is covered with perforated sheet-metal plates V, or their equivalents, attached to and lying flush with each face thereof by means of bolts 50 V' or otherwise, so that when the filter-plates are interposed between the distance-frames these perforated plates form a wall for the frames on each side thereof, thus leaving a hollow open space W between each pair of 55 frames, into which the liquid portion of the swill is drained from the cakes formed by the solid portion retained in the distance-frames.

A groove X is formed in the bottom bar of each filter-plate leading to a drain-spout Y, 60 attached to the plate at or near the lower corner thereof, so that the liquid will be drained from the frames and plates as rapidly as expressed.

65 As a means for supporting the perforated plates V of the filter-plates I prefer to form the filter-frames in the shape of a gridiron provided with a series of longitudinal ribs a,

extending vertically between the top and bottom bars of the frame and of sufficiently less width than the frame-bars to permit of the 70 countersinking of the perforated plates flush with the outer faces of said bars. These gridiron-bars, occurring as they do at intervals, serve to prevent the crushing or inward bending of the perforated plates under the pressure of the solid portions of the swill in the distance-frames, furnishing a support at intervals extending over the entire area of the plates, and these bars may obviously be provided either by a casting integral with the 75 outside or rectangular frame of the filter-plates or they may be separate pieces set into the frame, as shown in the drawings.

To prevent clogging of the passages through the lugs of the filter-plates connecting the distance-frames, which may occur with some classes of swill, I prefer to employ a stirrer consisting of a rod b, square, triangular, or other irregular form in cross-section, journaled at one end in the head F and at the opposite end in a suitable stuffing-box c in the pipe u, at which latter end it is also provided with a crank-handle d for convenience of manipulation, so that whenever the passages become clogged, or at such intervals as may be 95 deemed desirable, a few turns may be given to this stirring-rod, which latter serves to so loosen the swill in the passages that the pressure of the feed will be sufficient to force the swill through and remove the clog. Thus 100 it will be seen that by the employment of my distance-frames the cakes may be formed of any desirable thickness and without the necessity for changing the size of the filter-plates, by which the cakes are effectually 105 separated from each other, and that by reason of the double feed employed cakes of any thickness may be readily and rapidly formed, the overhead feed serving principally to fill the frames, while the supplemental feed 110 serves to both fill the frames and force the overflow into the next frame, and thus avoid the possibility of choking the passages between the frames through the filter-plates, although it is not absolutely essential that 115 this double feed should be employed.

In practice, after the frames and filter-plates are properly set up in the machine, supported as before described, the piston-head F is operated so as to force all of the 120 frames tightly together between it and the fixed end A, after which lock-nut a, working upon the guide-bars D, which are screw-threaded near the rear ends thereof for their reception, are turned up so as to lie closely 125 against the eyes G of the piston-head and securely lock it in position, after which the pressure of the ram may be released, or, if desired, where a lesser number of frames and plates are employed, a removable filling-sleeve b may be employed, slotted on one side, so as to fit on the guide-bars and thus avoid the necessity for running the nuts a considerable distance back and forth upon the bars 130

with each change in the number of frames and plates. The swill is then fed into the frames, preferably under suitable pressure, until all of the frames are completely filled, 5 after which the frames may be removed bodily from the machine or the cakes removed separately from the frames and the latter immediately prepared for another operation; but in no case, whether the frames are removed or not, need the filter-plates be removed, and obviously any number of frames and plates may be employed in a single operation, from one to the full capacity of the machine.

15 In conclusion I may state that between the feed-pipes R and the distance-frames there is a detachable connection of some suitable character not necessary to be either shown or described, which enables the ready removal 20 of the frames from the machine.

Having described my invention, what I claim, and desire to secure by Letters Patent, is—

1. In a filter-press, the combination, with a 25 series of filter-plates provided with perforations in the top bar thereof, of a series of distance-frames interposed between and alternating with said plates, the upper bars of which are provided with perforations open- 30 ing into the interior of said frames and registering with the perforations of said plates, and a feed-pipe registering with the perfora-

tion in the end filter-plate, substantially as described.

2. In a filter-press, the combination, with a 35 series of filter-plates provided with perforations in the top bar thereof, of a series of distance-frames interposed between and alternating with said plates, the upper bars of which are provided with perforations open- 40 ing into the interior of said frames and registering with the perforations of said filter-plates, a feed-pipe registering with the perforations in the end filter-plate, and a stirrer working through said feed-pipe and the perforations in said plates and frames, substantially 45 as described.

3. In a filter-press, the combination, with a series of filter-plates the top bar of each of which is perforated at the center of length 50 thereof, of a series of distance-frames alternating with said plates, the top bar of each of which at the center of length is provided with vertical and horizontal perforations opening into the interior of said frames, the 55 latter registering with the perforations in said plates, feed-pipes leading to each of said vertical perforations, and a supplemental feed-pipe registering with the perforation in the end filter-plate, substantially as described. 60
